UNITED STATES PATENT OFFICE.

DAVID S. HULFISH, OF TORONTO, ONTARIO, CANADA.

AUTOMATIC TELEPHONE SYSTEM.

1,418,187.

Specification of Letters Patent. Patented May 30, 1922.

Application filed May 27, 1918. Serial No. 236,833.

To all whom it may concern:

Be it known that I, DAVID S. HULFISH, a citizen of the United States of America, residing at Toronto, in the county of York 5 and Province of Ontario, Canada, have invented new and useful Improvements in Automatic Telephone Systems, of which the following is a specification.

My invention relates to improvements in 10 automatic telephone systems and the objects of my invention are to provide an improved circuit system for connecting automatic switches for service, as illustrated in the accompanying drawings, and as described 15 herein.

In the drawings: Fig. 1 shows section of switch and contact bank on line 1—1 of Fig. 2. Fig. 2 shows front elevation of switch with contact bank omitted. Fig. 3 shows 20 driving devices. Figs. 4, 5, 6, 7, 8, 9 unite to form a large circuit diagram and show a system of circuits for giving telephone service.

Referring to Figs. 1 and 2: The movable 25 brushes 201, 202 carried by insulation upon brush shaft 203 engage the under surfaces of eligible contacts 204, held fixed in the contact bank upon insulating plate 206. The contact bank comprises a plurality of levels 30 of contacts, many known methods of construction being available. Each level has two brushes as shown, each brush having a feed contact 205 fixed in the contact bank. The feed contacts are in the level of the 35 eligible contacts. The brushes shown, 201 and 202, engage the under surfaces of the feed contacts as well as of the eligible contacts, hence the brush may pass the feed contact. Alternate levels have brushes 40 above instead of below. The contact bank comprises contact bank plates 206 and contacts 204, 205, rigidly held together and attached to fixing plates 207, the fixing plates being then fixed upon vertical supporting 45 plates 208. Dowels 255 are fixed in parts 207 and pass through holes in switch body-plate 209. The faces of parts 207 engage the back face of part 209.

Body plates 209 has flanges 210 formed integrally therewith and supporting brush carrying shaft 203 and armature shaft 211. The brush carriage comprises shaft 203, hub 212, ratchet 213, brush spacers 214 of insulation, feed-contact guides 215 of insulation, 55 brushes 201, 202, clamp 216, and screws 217 which thread into hub 212 and clamp all

parts. The alinement of brushes is attained by insulating dowels 218.

Main spring 219 attached to hub 212 and flange 210 turns brush carriage when double pawl 220 permits and the brushes pass from contact to contact, advancing a half-step when armature 221 has been attracted and the remaining half-step when armature has been returned to normal by armature spring 60 256. A brush may be shaped to engage a contact while the armature is normal or while the armature is attracted, or both. A brush at one end of its travel may rest upon its own feed contact. Armature carrier 222, 65 carrying armature 221 and double pawl 220, is carried by armature shaft 211 between spacing sleeves 223, and is pulled by spring 256. Magnet support 224 supports magnets 225 and clutch-arm guide 226. Clutch arm 70 75 227 is pivoted upon ratchet 213, rests upon wing 228 of guide 226 and is drawn against the guide by spring 229. Clutch tooth or thrust member 230 is clamped upon drive shaft 231. Drive shaft 231 oscillates continually through a predetermined angle. Normal switch 232 comprises two contact 80 springs mounted upon bracket 233 upon supporting bar 208, tending to open, held closed by part 226 and spring 234. Clutch arm 227 85 is shown in three positions, solid line in normal position, dash line awaiting restoration, and dot-dash line at close of thrust of clutch hook. Parts 230 and 236 are shown in dot-dash line in their positions at the time part 90 227 occupies its dot-dash position.

The operation of the switch is as follows: Repeated electrical currents through magnets 225 operate armature 221 repeatedly and the brush carriage moves step-by-step 95 until a desired selective position is attained. For restoration to normal, further repeated or intermittent currents operate the armature, the brush carriage moves, the clutch arm 227, propelled by ratchet 213, passes its corner 100 235 beyond guide 226, and spring 229 draws the clutch arm into path of clutch tooth 230, as shown in dot line in Fig. 2. The clutch tooth engages the clutch arm and forces the clutch arm to position shown in dot-dash 105 line in Fig. 2, thus restoring the brush carriage to normal. The clutch-arm corner 235 has forced guide 226 to position shown in dot-dash line, thus opening normal switch 232 as shown in dot-dash line. Tooth 230 retires and disengages itself from arm 227, spring 234 pulls guide 226 to normal posi- 110

tion, closes normal switch 232 and lifts arm 227 to normal position as shown in solid line. By determining the dimension of the double pawl 220 between the faces which engage the ratchet, the relative lengths of the first and second steps of the ratchet and brushes for each ratchet tooth may be determined.

The devices for driving the shaft 231 are as follows: Motor 236 (Fig. 3) drives power wheel 237, link 238 and driving arm 239 upon shaft 231. The shaft 231 oscillates continually as indicated by the double-head curved arrow.

Switches of the type described may be organized by electric circuits and associated with telephones and callsenders to give an automatic telephone service. A system of circuits is shown in the drawings, the figures uniting at the margins where conductors of similar labels meet. Each switch has contact-levels sufficient in number for its requirements, the levels being numbered at the ends. The contacts in each level are numbered below. Each contact is represented by a circle; each brush by a rectangle united by a conductor-line to its feed contact.

A brush shaped to engage one contact but not two contacts at the same time is shown by a rectangle, as 103—7—0. A brush shaped to engage two contacts at the same time, thus holding unbroken connection with a series of contacts, is shown by a longer rectangle, as 103—6—0. A brush shown between contacts will engage a contact at the half-step, as 104—5—0 and 104—6—0. A brush shown in an advanced position upon a contact, as 103—14—25, will break from the contact at half-step, its engagement at half-step with the succeeding contact being immaterial. A brush shown in a retarded position upon a contact, as 103—13—25, will not engage the succeeding contact at half-step, its break at half-step from the preceding contact being immaterial. A pair of staggered brushes, as 103—13—25 and 103—14—25, upon contacts connected in pairs as shown, will be disconnected from each other at half-step and will be connected together at full-step. This arrangement of brushes facilitates adjustment for interruptions at half-step or full-step.

The callsender may be of any known type, the electrical contact members being arranged as required.

In the drawings, numbers under 30 are location numbers for identifying contacts. A contact is identified by giving first the label of the switch, then the level number, then the contact number in the level; thus, 103—2—6, meaning switch 103, level 2, contact 6. A brush is identified by the location of its feed contact. The position of a switch, or of the brushes in the switch, is identified by giving two occupied contacts;

thus in the diagram the pilot is shown at 1—13 while the groupfinder 102 is in position 0—12. Labels of four figures indicate duplicated apparatus, the first three figures identifying the apparatus duplicated. 70 Switches 101, 105, 108 and 403 have some of their levels omitted from the diagram. Switch 101 engages its clutch members for mechanical restoration when its brushes reach contacts 12—and—24, the brushes then 75 being restored to contacts 1—and—13. Switches 102, 104, 105, 107, 108, 402 and 403 restore from 12—and—24 to 0—and—12. Although the normal position of switch 103 is on 1 and 13, switches 103, 106 and 401 re-store from 11—and—23 to 0—and—12. This variation is attained by adjusting the setting of the hook 230 on shaft 231, by the setting of stops and springs of 232 as affecting guide 226 and by predetermining in manufacture 85 the length of clutch arm 227.

The automatic switches are grouped into "sets" or "divisions" which are duplicated as required to serve the traffic. A "1st set" or "primary set" of switches comprises 1st 90 pilot 103, groupfinder 102, linefinder 101, 1st register 104, and 1st searcher 105. A "2nd set" or "interconnector set" comprises 2nd pilot 106, 2nd register 107 and 2nd searcher 108. A "final set" comprises final 95 pilot 401, final register 402 and final connector 403.

The 1st set finds the calling line, registers the 1st digit called for, and finds an idle 2nd set. The 2nd set or first interconnector set 100 registers the 2nd digit called for and finds an idle final set. The final set registers the last two digits called for and sends a "completion" signal and a "ringing starting" signal to 1st pilot which then rings, registers and releases. Additional "interconnector sets" may be connected between the 2nd set and the final set to increase the total number of lines served.

Each telephone line has two relays, line 110 relay 130 and cut-off relay 131 constituting a relay set for telephone 156, having directory number 36. Line relays, as 130 and 1302, which pertain to the same half-level of the linefinder 101, are grouped upon a 115 common wire, as 318 or 319, extending to the groupfinder 102, identifying the groupfinder position for those lines. Line relays, as 1302 and 1303, which pertain to the same linefinder position, are grouped upon a similar common wire, as 316 or 317, identifying the linefinder position for those lines.

Circuits are referred to by numbers, C1, C2, etc.

The operation is as follows:

A lifted receiver at telephone 156 by its hookswitch closes C1 and charges line relay 130. Then line relay 130 by C1.1 charges starting relay 132.

C1. "Line." Battery, helix of 130, points 130

of 131, telephone 156, points of 131, earth.

C1.1. "Starting relay." Battery, helix of starting relay 132, wire 389, points of line relay 130, earth.

5 Starting relay 132 closes C2 to charge linefinder magnet 121 repeatedly and C2.1 to charge groupfinder magnet 122 repeatedly, these circuits being interrupted respectively by brushes 101-18-25 and 102-6-25 at 10 the half-step, until test brushes 101-18-0 and 102-6-0 close searching circuits C3 and C3.1, respectively. C3 then charges relay 42 which opens C2; and C3.1 charges relay 44 which opens C2.1. Relays 42 and 44 15 jointly close C4 to charge the pilot magnet. Pilot brushes pass to position 2-14.

C2. "Linefinder drive." (Pilot 1-13.)

Battery, linefinder magnet 121, normal switch 111, brushes 101-18-25, 101-17-25, 20 101-16-25 and contacts 12-to-23, wire 307, 103-12-1, 103-11-1, wire 306, relay 42 points, wire 305, 103-11-13, wire 304, relay 132 points, earth.

C2.1. "Groupfinder drive." (Pilot 1-13.)

25 Battery, groupfinder magnet 122, normal switch 112, brushes 102-6-25, 102-5-25, 102-4-25 and contacts 12-to-23, wire 310, 103-10-1, 103-9-1, wire 309, relay 44 points, wire 308, 103-13-1, 103-14-1, 30 103-11-13, wire 304, relay 132 points, earth.

C3. "Linefinder test." (Pilot 1-13.)

Battery, relay 42 helix, wire 314, 103-9-13, 35 103-10-13, wire 315, 101-18-6, wire 317, relay 130 points, earth.

C3.1. "Groupfinder test." (Pilot 1-13.)

Battery, relay 44 helix, wire 320, 103-7-13, 40 103-8-13, wire 324, 102-6-3, wire 318, wire 389, relay 130 points, earth.

45 C4. "Pilot magnet." (Pilot 1-13.)

Battery, pilot magnet 123, normal switch 113, 103-18-13, 103-17-13, 103-16-13, wire 327, relay 44 points, wire 326, 103-6-13, 103-5-13, wire 325, relay 42 50 points, wire 305, 103-11-13, wire 304, relay 132 points, earth.

With pilot in position 2-14, C5 charges relay 42 (relay 41 remaining uncharged) and C6 charges pilot magnet 123. Pilot 55 passes to position 3-15.

C5. "Loop test." (Pilot 2-14.) Battery, relay 42 helix, wire 314, 103-5-2, wire 311, 102-1-3, 101-13-6, wire 361, wire 301, telephone 156, wire 302, relay 131 55 points, earth.

C6. "Pilot magnet." (Pilot 2-14.) Battery, pilot magnet 123, normal switch 113, 103-14-14, 103-13-14, 103-12-14, wire 334, relay 41 points, wire 330, 103-6-14, 60 103-5-14, wire 325, relay 42, points, wire 305, 103-11-14, wire 304, relay 132 points, earth.

Were lines 156 (groupfinder 3 linefinder 6) and 1563 (groupfinder 8 linefinder 3) 65 waiting contemporaneously with relays 130

and 1303 charged and earth on indicator wires 317, 318, 319, linefinder 101 would stop on 101-18-3 for line 1562 (groupfinder 3 linefinder 3) in error; then with pilot 2-14, either (a) with line 1562 idle C5 would not 70 be formed to charge relay 42, and C2 would drive linefinder 101 further, or (b) with line 1562 busy, C5.1 would charge relay 41, and C5.2 would drive linefinder 101 further. Thus C2 and C5.2 alternatively would 75 drive the line finder 101 to 101-18-6 for line 156, where relay 42 would charge and relay 41 would not charge and C6 would be formed to advance the pilot to 3-15.

C5.1. "Guard test." (Pilot 2-14.) Battery, wire 373, wire 363, 101-15-6, 102-3-3, wire 313, 103-4-2, wire 329, relay 41 helix, earth.

C5.2. "Linefinder drive." (Pilot 2-14.) Battery, linefinder magnet 121, normal switch 111, brushes 101-18-25, 101-17-25, 80 101-16-25, and contacts 12-to-23, wire 307, 103-13-2, 103-14-2, wire 335, relay 41 points, wire 330, 103-6-14, 103-5-14, wire 325, relay 42 points, wire 305, 90 103-11-14, wire 304, relay 132 points, earth.

With pilot in position 3-15, C7 charges cut-off relay 131 and C8 charges calling feed relay 42 and signal relay 41. C6.1 charges 95 pilot magnet 123 and pilot brushes pass to position 4-16.

C7. "Calling guard." (Pilot 3-15.) Battery, resistance 134, wire 336, 103-4-3, wire 313, 102-3-3, 101-15-6, wire 363, 100 relay 131 helix, earth.

C8. "Calling loop." (Pilot 3-15.) Battery, relay 42 helix, wire 314, 103-5-3, wire 311, 102-1-3, 101-13-6, wire 361, wire 301, telephone 156, wire 302, wire 362, 105 101-14-6, 102-2-3, wire 312, 103-6-3, wire 329, relay 41 helix, earth.

C6.1. "Pilot magnet." (Pilot 3-15.) Battery, pilot magnet 123, normal switch 113, 103-14-15, 103-13-15, 103-12-15, 110 wire 335, relay 41 points, wire 330, 103-2-15, earth.

The next action is to adjust the 1st register or "thousands" switch 104, to the numerical position required to select ultimately 115 the desired line to be called, by control of the callsender at the telephone, and then to shift the pilot brushes as a "changeover" switch by joint control of the signal relay 41, the register 104 and the changeover relay 45. 120

The callsender when operated moves 151 to break from 152 to open C8 a predetermined number of times, meanwhile holding shunt switch 150 closed. Signal relay 41 thus is released several times rapidly to effect 125 the adjustment of register switch 104 and changeover of pilot 103.

To adjust switch 104, relay 41 closes C9 repeatedly. To prevent shift of switch 103 before the end of adjustment of 104, relay 130

41 sends by C10 a set of impulses to change-over relay 45; and switch 104 also sends by C10.1 and C10.2 two sets of impulses to relay 45, the three sets of impulses being concurrent but out of phase so that the points of 45 are held operated until after impulses cease in C9 and C10. When 45 is finally released it closes C11 to charge the pilot magnet.

10 An impulse in C10 ceases when 41 is recharged but the first companion impulse in C10.1 continues until after 124 in C9 has been magnetically discharged, until after armature 221 of 124 has been released and 15 retracted to permit dog 220 to clear from tooth of ratchet 213, and until mainspring 219 has moved the brushes as a mass so far that brush 104-6-0 has broken contact from its contact; this succession in time in 20 the termination of the two companion impulses I am describing briefly by saying that the impulses are concurrent but out of phase. After this, when brushes of 104 move still further, brush 104-4-0 engages its next 25 contact and sends a second companion impulse over C10.2 to charge 45 further. The two relays 41 and 45 are preferably alike in mechanical construction, the delay by phase displacement of the impulses to 45 being such that, in a series of signals, 41 is re-discharged to re-charge 45 before 45 can close C11 and operate the pilot switch. The 30 current through C10.2 charges the change-over condenser 53 which subsequently is discharged by C10.3. The greater the capacity of the changeover condenser 53, the greater will be the effect upon the changeover relay 45. To avoid large currents in the change-over condenser discharge, a resistance 54 is 35 included in its circuit.

40 C9. "Numerical." (Pilot 4-16.) Battery, register magnet 124, normal switch 114, wire 338, 103-5-16, 103-6-16, wire 334, signal relay 41, points, wire 330, 103-2-16, 45 earth.

45 C10. "Changeover relay." (Pilot 4-16.) Battery, right helix of changeover relay 45, wire 345, 103-8-16, 103-7-16, wire 334, of signal relay 41, points, wire 330, 103-2-16, earth.

50 C10.1. "Changeover auxiliary." (Pilot 4-16.) Battery, left helix of relay 45, wire 346, 103-10-16, 103-9-16, wire 339, 104-6-1, (104 at half-step), earth.

55 C10.2. "Second auxiliary." (Pilot 4-16.) Battery, left helix of relay 45, wire 346, 103-10-6, 103-9-16, wire 339, 104-4-1, condenser 53, resistance 54, earth.

60 C10.3. "Condenser discharge." Earth, resistance 54, condenser 53, 104-5-2, earth.

65 C11. "Changeover." (Pilot 4-16.) Battery, pilot magnet 123, normal switch 113, 103-14-16, 103-13-16, 103-12-16, wire 340, changeover relay 45 points, wire 344, 104-5-16 (or as adjusted), earth.

Pilot brushes move to 5-17. With pilot 103 at 5-17, searcher 105 finds an idle interconnector set. C12 and C12.1 charge searcher magnet 125 to advance the brushes of 105 until test relay 43 is charged by C13, 70 when C13.1 charges pilot magnet 123, and pilot 103 passes to position 6-18.

C12. "Searcher drive." (Pilot 5-17.) Battery, searcher magnet 125, normal switch 115, 105-20-12, wire 347, 103-5-17, 75 103-6-17, wire 348, relay 43 points, wire 356, 103-4-17, earth.

C12.1. "Searcher drive." (Pilot 5-17.) Battery, searcher magnet 125, normal switch 115, brushes 105-20-25, contacts 13-to- 80 23, wire 349, 103-8-17, 103-7-17, wire 348, 43 points, wire 356, 103-4-17, earth.

C13. "Searcher test." (Pilot 5-17.) Earth, helix of relay 43 used for test, wire 328, 103-3-5, wire 323, 104-3-4 or as 85 adjusted, brush 105-18-0 moving to an idle trunk, 105-18-3, wire 333, 108-18-12, 107-3-12, 106-4-1, helix of interconnector holding relay 182, battery, earth.

C13.1. "Pilot magnet." (Pilot 5-17.) 90 Battery, pilot magnet 123, normal switch 113, 103-14-17, 103-13-17, 103-12-17, wire 354, relay 43 points, wire 356, 103-4-17, earth.

Pilot 103 passes to position 6-18, substitutes earth of 103-3-6 for relay 43 in C13, and awaits "completion signal" over C23. Relay 182, the interconnector holding relay, is charged but has no effect beyond lighting the interconnector pilot lamp 162.

The next action is to adjust the interconnector register or "hundreds" switch 107 to the numerical position required, by control of the callsender at the telephone, and then to shift the brushes of the interconnector pilot 106 as a changeover switch by joint 105 control of the signal relay 41, the register 107 and the interconnector changeover relay 183. The method is the same as in adjusting the first register.

110 The callsender releases signal relay 41 several times rapidly. Relay 41 closes C14 repeatedly which adjusts switch 107 numerically, while by branch circuit C14.1 a set of impulses is sent to changeover relay 183. Switch 107 also sends by C14.2 and C14.3 two sets of impulses to relay 183. C14.4 discharges condenser 184. When relay 183 is finally released, it closes C15 and charges interconnector pilot magnet 126, passing interconnector pilot brushes to 2-14.

115 C14. "Numerical." (1st pilot 6-18; 2nd pilot 1-13.) Earth, 103-2-18, wire 330, points of signal relay 41, wire 334, 103-1-6, wire 321, switches 104, 105 as adjusted, wire 331, 106-1-1, wire 384, normal switch 117, interconnector register magnet 127, battery, earth.

120 C14.1. "Changeover relay." (1st pilot 6-18; 2nd pilot 1-13.) Earth, 103-2-18, 130

- wire 330, points of signal relay 41, wire 334, 103—1—6, wire 321, switches 104, 105 as adjusted, wire 331, 106—5—1, interconnector changeover relay 183, battery, earth.
- 5 C14.2. "Auxiliary." (2nd pilot 1—13.) Battery; relay 183, wire 385, contact and brush 107—6—25 at half-step, earth.
- C14.3. "Second auxiliary." (2nd pilot 1—13.) Battery; relay 183, wire 385; contact and brush 107—4—25, condenser 184, resistance 185, earth.
- C15. "Changeover." (2nd pilot 1—13.) Battery, 2nd pilot magnet 126, normal switch 116, 106—1—13, wire 386, brush 107—4—0 as adjusted, wire 387, points of relay 183, earth.
- C14.4. "Condenser discharge." Earth, resistance 185, condenser 184, brush 107—5—25 at half step, earth.
- 20 With pilot 106 at 2—14, searcher 108 finds an idle final set. C16 and C16.1 charge searcher magnet 128 to advance the brushes of searcher 108 until test relay 186 is charged by C17 and in turn charges magnet 126 by C18, advancing pilot 106 to position 3—15. Pilot 106 in position 3—15 substitutes earth for relay 186 in C17, connects wire 331 to 341 and 332 to 342 and becomes inert in the further action of the call served,
- 25 30 awaiting release by discharge of holding relay 182 when C13 will have been broken by pilot 108.
- C16. "Interconnector searcher drive." (2nd pilot 2—14.) Battery, searcher magnet 128, normal switch 118, 108—15—12, 106—4—14, points of test relay 186, earth.
- C16.1 "Interconnector searcher drive." (2nd pilot 2—14.) Battery, searcher magnet 128, normal switch 118, 108—15—25, contacts 13—to—23, 106—5—14, points of test relay 186, earth.
- C17. "Interconnector test." (2nd pilot 2—14.) Earth, helix of test relay 186, 106—3—2, 107—3—5 or as adjusted, brush 108—18—0 moving to an idle trunk, wire 343, 403—18—12, wire 374, 402—3—12, 401—6—1, final holding relay 192, battery, earth.
- C18. "Interconnector pilot magnet." (2nd pilot 2—14.) Battery, pilot magnet 126, 50 normal switch 116, 106—1—14, points of test relay 186, earth.
- Since the interconnector effaces itself when adjusted, additional interconnectors may be connected between switches 108 and 401 to increase the total number of telephone lines served by the exchange, or all interconnector sets may be omitted for economy if the size of the exchange permits.
- The next action is to adjust the final register or "tens" switch 402 to the numerical position required, by control of the callsender at the telephone, and then to shift the final pilot 401 as a changeover switch, by joint control of signal relay 41, register 402 and
- final changeover relay 193. The method is the same as in adjusting the first register.
- The callsender releases signal relay 41 several times rapidly. Relay 41 closes C19 repeatedly which adjusts switch 402 numerically, while by branch circuit C19.1 a set of impulses is sent to changeover relay 193. Switch 402 also sends by C19.2 and C19.3 two sets of impulses to relay 193, concurrent but out of phase. When relay 193 is finally released, it closes C20 and charges final pilot 75 magnet 421.
- C19. "Numerical impulses." (1st pilot 6—18; final pilot 1—13.) Earth, 103—2—18, points of signal relay 41, wire 334, 103—1—6, wire 321, switches 104, 105 as adjusted, wire 331, 106—1—3, switches 107, 108 as adjusted, wire 341, 401—4—1, normal switch 412, final register magnet 422, battery, earth.
- C19.1. "Changeover relay." (1st pilot 6—18; final pilot 1—13.) Earth, 103—2—18, 85 points of signal relay 41, wire 334, 103—1—6, wire 321, switches 104, 105 as adjusted, wire 331, 106—1—3, switches 107, 108 as adjusted, wire 341, 401—1—1, final changeover relay 193, battery, earth.
- C19.2. "Auxiliary." (Final pilot 1—13.) Battery, relay 193, wire 366, brush 402—6—25 at half-step, earth.
- C19.3. "Second auxiliary." (Final pilot 1—13.) Battery, relay 193, wire 366, brush 95 402—4—25, 401—5—1, condenser 194, resistance 195, earth.
- C20. "Changeover." (Final pilot 1—13.) Battery, final pilot magnet 421, normal switch 411, 401—1—13, contact and brush 100 402—4—0, wire 365, points of final changeover relay 193, earth.
- C19.4. "Condenser discharge." (Final pilot 1—13.) Earth, resistance 195, condenser 194, 401—5—1, brush 402—5—25, 105 contact, earth.
- Final pilot shifts to 2—14.
- The next action is to adjust the final connector or "units" switch 403 to the numerical position required, by control of the callsender at the telephone, and to shift the final pilot 401 as a changeover switch, by joint control of signal relay 41, final switch 403 and final changeover relay 193. The method is the same as in adjusting the final register. 110
- The callsender releases signal relay 41 several times rapidly. Relay 41 closes C21 repeatedly which adjusts switch 403 numerically, while by branch circuit C19.1 a set of impulses is sent to changeover relay 193. 120 Switch 403 also sends by C21.2 and C21.3 two sets of impulses to relay 193. When relay 193 is released, it closes C22 and charges final pilot magnet 421.
- C21. "Numerical impulses." (1st pilot 125 6—18; final pilot 2—14.) Earth, 103—2—18, points of signal relay 41, wire 334, 103—1—6; wire 321, switches 104, 105 as adjusted, wire

- 331, switches 106, 107, 108 as adjusted, wire 341, 401—4—2, wire 375, normal switch 413, final connector magnet 423, battery, earth.
- 5 C21.2. "Auxiliary." (Final pilot 2—14.) Battery, relay 193, wire 366, wire 367, contact and brush 403—20—0, earth.
- 10 C21.3. "Second auxiliary." (Final pilot 2—14.) Battery, relay 193, wire 366, wire 367, contact and brush 403—19—25, wire 368, 401—5—2, condenser 194, resistance 195, earth.
- 15 C22. "Changeover". (Final pilot 2—14.) Battery, final pilot magnet 421, normal switch 411, 401—1—14, contact and brush 403—19—0, wire 380, wire 365, points of changeover relay 193, earth.
- 20 C21.4. "Condenser discharge." (Final pilot 2—14.) Earth, resistance 195, condenser 194, 401—5—2, wire 368, brush 403—20—25, contact, earth.
- 25 Final pilot shifts to 3—15, sends "completion signal" C23 to 1st pilot and makes test upon selected line for idle or busy condition. At 1st pilot, C23 charges test relay 44 which locks over C23.1 and by C23.2 passes pilot 103 to position 7—19, where C23.3 is formed to pass it to 8—20. At the final pilot, if the selected line be found idle, 30 an "idle test" circuit C24 charges final pilot magnet 421 and final pilot passes to 4—16, then C25 charges the final pilot magnet repeatedly and final pilot passes to position 9—21, there charging cutoff relay 1312 by 35 C27. During these acts, the interconnector sets, if any, are inert.
- 40 C23. "Completion." (1st pilot 6—18; final pilot 3—15.) Battery, relay 44 helix, wire 320, 103—2—6, wire 322, switches 104 and 105 as adjusted, wire 332, switches 106, 107, 108 as adjusted, wire 342, 401—2—3, earth.
- 45 C23.1. "Locking." (Pilot 6—18.) Battery, relay 44 helix, wire 320, 103—7—18, 103—8—18, wire 327, relay 44 points, wire 326, 103—9—18, 103—10—18, earth.
- 50 C23.2. "Pilot magnet." (Pilot 6—18.) Battery, pilot magnet 123, normal switch 113, 103—14—18, 103—13—18, 103—12—18, wire 355, relay 44 points, wire 308, 103—13—6, 103—14—6, earth.
- 55 C23.3. "Pilot magnet." (Pilot 7—19.) Battery, pilot magnet 123, normal switch 113, 103—14—19, 103—13—19, 103—12—19, earth.
- 60 C24. "Idle test." (Final pilot 3—15.) Battery, final pilot magnet 421, normal switch 411, 401—1—15, relay 196 points, earth.
- 65 C25. "Final pilot magnet." (Final pilot 4—16 to 8—20.) Battery, final pilot magnet 421, normal switch 411, 401—1—16, earth.
- 70 There are two speaking positions for pilot 103. If conversation is held when pilot is in position 8—20, meter circuit C32 will be formed and meter 163 will be operated; but if conversation is held when pilot is in position 9—21, meter circuit C32 will not be formed in switch 103.
- 75 The selected line being a "free service" line, being a line such as 3713, 3723, 3733, current over C26 through the line relay and through reversed jumpers on the intermediate distributing frame, charges non-metering-test relay 43 (without charging its companion relay 44) which by C26.1 charges relay 47 which in turn locks by C26.2 and C26.3 charges pilot magnet 123 and first pilot advances to non-metering position 9—21. If the selected line is not "free service", C26 is not formed.
- 80 C26. "Non-metering test". (1st pilot 8—20; final pilot 5—17 to 7—19.) Battery, (Fig. 4) line relay 1303 helix, cutoff relay 1313 points, reversed wire on terminals, wire 3723, (to Fig. 9) switches 403, 402 as adjusted, 401—2—5, wire 342, switches 108, 107, 106 as adjusted, wire 332, switches 105, 104 as adjusted, wire 322, 103—2—8, wire 90 328, relay 43 helix, earth.
- 85 C26.1. "Non-metering test local." (Pilot 8—20.) Battery, resistance 134, wire 336, 103—4—8, 103—11—8, 103—12—8, wire 354, charged relay 43 points, wire 356, 103—14—8, 103—13—8, wire 308, uncharged relay 44 points, relay 47 helix, 103—4—20, earth.
- 90 C26.2. "Locking." (Pilot 8—20.) Earth, 103—4—20, relay 47 helix, relay 47 points, wire 354, 103—12—8, 103—11—8, 104—4—8, wire 336, resistance 134, battery, earth.
- 95 C26.3. "Pilot magnet." (Pilot 8—20.) Battery, pilot magnet 123, normal switch 113, 103—14—20, 103—13—20, 130—12—20, relay 47 points, earth.
- 100 C27. "Answering guard." (Final pilot 8—20 and 9—21.) Battery, resistance 133, 401—3—9, switches 402 and 403 as adjusted, wire 3733, helix of cutoff relay 1313 (Fig. 4), earth.
- 105 While transiently in position 8—20, final pilot closes ringing-starting circuit C28 to charge relay 44 which in turn by C28.1 charges ringing relay 46 which locks by C28.2 and alternating ringing current is 110 passed over C30, through the callbell of the selected line and through ringing release relay 48 to earth, the relay 48 being not operated because of the condenser in the callbell circuit. When the receiver of the called line 115 is lifted, relay 48 is operated, releasing relay 46. Answering loop C31 then is formed charging relays 43 and 44 and forming C32 to operate meter 163 by shunting resistance 134 if the pilot is in position 8—20. Conversation is over C33 formed from C8 and C31 through condensers 131 and 132.
- 120 C28. "Ringing starting." (1st pilot 8—20;

- final pilot 8—20.) Battery, helix of relay 44, points of relay 46, wire 358, 103—1—8, wire 321, switches 104, 105 as adjusted, wire 331, switches 106, 107, 108 as adjusted, wire 5 341, 401—1—8, earth.
- C28.1. "Ringing relay." (Pilot 8—20.) Battery, 103—10—8, 103—9—8, wire 355, points of charged relay 44, wire 308, 103—13—8, 103—14—8, wire 356, points of uncharged relay 43, wire 348, 103—6—20, 103—5—20, helix of ringing relay 46, earth.
- C28.2. "Locking." Battery, helix of ringing relay 46, points of ringing-release relay 48, points of ringing relay 46, earth.
- 15 C30. "Ringing." (1st pilot 8—20; final pilot 9—21.) Battery, ringing generator 145, ringing commutator 154; resistance 155, points of charged ringing relay 46, wire 358, 103—1—8, wire 321, switches 104, 105 as adjusted, wire 331, switches 106, 107, 108 as adjusted, wire 341, 401—1—9, switches 402 and 20 403 adjusted, wire 3712, line wire 3012, call-bell and condenser of telephone set 1562, line wire 3022, wire 3722, switches 403 and 402 as 25 adjusted, 401—2—9, wire 342, switches 108, 107, 106 as adjusted, wire 332, switches 105, 104 as adjusted, wire 322, 103—2—8, wire 328, helix of relay 48, points of charged relay 46, earth.
- 30 C31. "Answering loop." (1st pilot 8—20 or 9—21; final pilot 9—21.) Battery, helix of relay 44, points of discharged relay 46, wire 358, 103—1—8, wire 321, switches 104, 105 as adjusted, wire 331, switches 106, 107, 35 108 as adjusted, wire 341, switches 401, 402, 403 as adjusted, wire 3712, line wire 3012, telephone set 1562, line wire 3022, wire 3722, switches 403, 402, 401, wire 342, switches 108, 107, 106 as adjusted, wire 332, switches 40 105, 104 as adjusted, wire 322, 103—2—8, wire 328, helix of relay 43, earth.
- C32. "Meter." (1st pilot 8—20, not 9—21.) Battery, 103—10—8, 103—9—8, wire 355, points of relay 44, wire 308, 103—13—8, 45 103—14—8, wire 356, points of relay 43, wire 354, 103—12—8, 103—11—8, 103—4—8, wire 313, switches 102, 101 as adjusted, wire 363, meter 163, earth.
- C33. "Speaking." (1st pilot 8—20; final 50 pilot 9—21.) From line conductors of C8 to 103—5—8, 103—8—8, wire 379, condenser 141, wire 376, 103—1—0, and to line conductors of C31; also from line conductors of C8 to 103—6—8, 103—7—8, wire 378, condenser 142, wire 377, 103—2—0, and to line conductors of C31.
- Should the selected line be busy, then with final pilot in position 3—15 busy-test circuit C34 would be formed, charging test relay 60 196 and preventing C24. Final pilot is held in position 3—15, 1st pilot is advanced to 8—20 by "completion signal" C23, and tone circuit C35 is formed.
- C34. "Busy test." (Final pilot 3—15.) 65 Battery, resistance 1332, switches 403 and 402 as adjusted, 401—3—3, helix of test relay 196, earth.
- C35. "Tone." (1st pilot 8—20; final pilot 3—15.) Earth, tone device 157, points of relay 196, 401—1—3, wire 341 and over 70 speaking circuit C33 to calling telephone and to wire 342, 401—2—3, earth.
- I divide the action of the automatic switches into two parts, first, "operation," by which a telephone call is given service, 75 and second, "restoration" by which used switches are returned to their normal condition of waiting, in readiness for service upon a subsequent call.
- In using the switches herein described, 80 the method of restoring each switch is to advance the switch electrically to its ultimate position, then to engage its mechanical power source and to restore it mechanically to its primary position. If all switches were 85 restored simultaneously C7 and C8 might be formed to certain lines through switches 103, 102, 101, while other "operation" circuits might be formed through other switches. To obviate or reduce this condition, I provide a method of restoring in which all switches are advanced to render them independent in "operating" circuits but dependent in certain "restoring" circuits, then are restored serially or in groups in 90 such order and in such manner that no "operating" circuit is formed to any telephone line during the action of "restoring," and ultimately are rendered again electrically dependent in their "operating" circuits by the 100 final act of restoration. In this method of restoration, the circuits in each restoring switch which might lead to telephone lines are held open in an associated switch while the restoring switch is returning to normal. 105
- Slow relay 49 charged by C8.1 has held its armature circuit open during the rapid operation of signal relay 41.
- Release is effected at any time by hanging up the calling telephone, breaking the calling loop C8, releasing relay 41 permanently, 110 thus releasing slow relay 49 to close pilot release circuit C40, and pilot 103 passes to position 10—22.
- C8.1. "Holding." (Pilot 4—16 to 9—21.) 115 Battery, helix of slow relay 49, points of signal relay 41, 103—2—16, earth.
- C40. "Pilot release." (Pilot 4—16 to 9—21.) Battery, pilot magnet 123, normal switch 113, brushes 103—14—25, 103—13—25, 103—3—25, contacts 16 to 21, points of 120 slow relay 49, earth.
- Pilot 103 in position 10—22 closes switch release circuit C41 which advances switches 101, 102, 104 and 105.
- C41. "Switch release." (Pilot 10—22.) 125 Battery, linefinder magnet 121, normal switch 111, brushes 101—18—25, 101—17—25, 101—16—25, contacts 14 to 23, wire 307, 103—13—10, 103—14—10, earth. Also bat-

tery, groupfinder magnet 122, normal switch 112, brushes 102—6—25, 102—5—25, 102—4—25, contacts 12 to 22, wire 310, 103—11—10, 103—12—10, earth. Also, battery, register magnet 124, normal switch 114, brush 104—6—25, contacts 13 to 22, wire 395, 103—2—22, earth. Also, battery, searcher magnet 125, normal switch 115, brush 105—20—25, contacts 13 to 23, wire 349, 103—4—22, earth. If switch 104 has not been operated from normal, C41 will not operate that switch. Likewise switch 105 and switch 101.

Switches 101 and 105 in position 12—24 engage their clutch members. Switches 102 and 104 in position 11—23 jointly close C42 to advance pilot to 11—23 to engage its clutch members.

With the next advancing swing of shaft 20 231 and hooks 230, switches 101 and 105 are restored to position 0—12, while the pilot 103 is restored mechanically to a pre-normal position beyond its electrical normal position, and stops with its brushes on contacts 25 0—12. During the reverse movement of these switches, no circuit is completed to any line because the brushes of switches 102 and 104 connecting circuits from 103 to 101 and from 103 to 105 are upon vacant contacts in 102 and 104.

C42. "Pilot clutch." (Pilot 10—22.) Battery, pilot magnet 123, normal switch 113, 103—14—22, 103—13—22, 103—12—22, wire 396, 102—3—23, wire 390, 104—5—23, 35 and earth. If switch 104 has not been operated from normal, C42 will be through 104—5—12.

Pilot in position 0—12 closes C43. Switches 102, 104 advance their brushes one 40 step, engage their clutch members upon the next swing of the clutch hooks, and return to normal position shown in the drawings, closing then C44 which advances the pilot to position 1—13, and completes restoration, 45 the switches becoming again electrically dependent for "operating" circuits and being again in readiness for further service in response to a calling telephone line.

C43. "Switch clutch. (Pilot 0—12.)" 50 Battery, register magnet 124, normal switch 114, 104—6—23, wire 398, 103—2—12, earth. Also, groupfinder magnet 122, normal switch 112, 102—6—23, 102—5—23, 102—4—23, wire 399, 103—4—12, earth. 55 If 104 has not been operated from normal, C43 does not operate that switch.

C44. "Pilot normaling." (Pilot 0—12.) Battery, pilot magnet 123, normal switch 113, 103—14—12, 103—13—12, 103—12—12, 60 wire 392, 102—2—12, wire 393, 104—4—12, earth.

The restoration of the 2nd set or interconnector set of switches is as follows:

The release of 1st pilot 103 has broken C13 65 and has released interconnector holding re-

lay 182. Relay 182 closes C45, charging 2nd pilot magnet 126 repeatedly and pilot 106 advances to 10—22, closing switch release circuit C46 which advances searcher 108 to 12—24 and register 107 to 11—23; register 70 107 at 11—23 closes circuit C47 and pilot 106 makes one step to 11—23. Searcher 108 at 12—24 and pilot 106 at 11—23 engage their clutch members and both are restored to 0—12. During their restoring movements, telephone line circuits between them and test C13 are open by the brushes of the register 107 upon vacant contacts.

C45. "Interconnector pilot magnet." (2nd pilot 2—14 to 9—21.) Battery, 2nd pilot 80 magnet 126, normal switch 116, brush 106—6—25, contacts 14 to 21, points holding relay 182, earth.

C46. "Interconnector switch magnets." (2nd pilot 10—22.) Battery, 2nd searcher 85 magnet 128, normal switch 118, brush 108—15—25, contacts 13 to 23, 106—5—22, points of relay 186, earth. Also, battery, 2nd register magnet 127, normal switch 117, brush 107—1—25, contacts 13 to 22, 106—4—22, 90 points of relay 186, earth.

C47. "Interconnector pilot magnet." (2nd pilot 10—22.) Battery, 2nd pilot magnet 126, normal switch 116, 106—6—22, 107—5—11, earth.

Pilot 106 in position 0—12 closes C48 to restore register 107; and when the register's normal switch closes after restoration of the register, C49 charges test relay 186 which by C18 (through 106—1—12) charges pilot 100 magnet 126 and pilot steps to its normal position 1—13, as shown in the drawings. C49 does not operate 127 because of resistance of 109 and 186.

C48. "Interconnector register magnet." 105 (2nd pilot 0—12.) Battery, 2nd register magnet 127, normal switch 117, 107—1—23, 106—4—12, points of relay 186, earth.

C49. "Interconnector pilot normaling." 110 (2nd pilot 0—12.) Battery, magnet 127, normal switch 117, resistance 109, 107—2—12, 106—2—12, helix of test relay 186, earth.

The interconnector pilot 106 now passes to position 1—13 and closes its test circuit C13, which had been open at 107—3—23 115 while 106 was restoring and at 106—4—0 while 107 was restoring. C13 is open also if the detachable part of the switch (body plate 209 and its brushes) are removed from any contact bank.

The restoration of the final set of switches is as follows:

The release of interconnector pilot 106 has broken C17 and has released final holding relay 192. Relay 192 closes C50, charging final pilot magnet 421, repeatedly and pilot 401 advances to 10—22, closing switch release circuit C51 which advances final connector 403 to 12—24 and final register 402 to 11—23; register 402 at 11—23 closes cir- 125 130

cuit C52 and final pilot 401 makes one step to 11—23. Final connector 403 at 12—24 and final pilot 401 at 11—23 engage their clutch members and both are restored to 5 0—12. During their movement, telephone line circuits between them are held open by the brushes of the register 402 upon vacant contacts.

C50. "Final pilot magnet." (Final pilot 10 2—14 to 9—21.) Battery, final-pilot magnet 421, normal switch 411, brush 401—6—25, contacts 14 to 21, points of final holding relay 192, earth.

C51. "Final switch magnets." (Final pilot 15 10—22.) Battery, final connector magnet 423, normal switch 413, brush 403—15—25, contacts 13 to 21, wire 320, 401—5—22, earth. Also, battery, final register magnet 422, normal switch 412, brush 402—1—25, 20 contacts 13 to 22, 401—4—22, earth.

C52. "Final pilot magnet." (Final pilot 10—22.) Battery, final pilot magnet 421, normal switch 411, 401—6—22, 402—5—11, earth.

25 Final pilot 401 in position 0—12 closes C53 to restore register 402; and when the register's normal switch closes after restoration of the register, C54 charges final test relay 196 which by C55 charges final pilot 30 magnet 421 and final pilot steps to its normal position 1—13, as shown in the drawings.

C53. "Final register magnet." (Final pilot 0—12.) Battery, final register magnet 422, normal switch 412, 402—1—23, 401—4—12, earth.

C54. "Final pilot normalizing." (Final pilot 0—12.) Battery, final register magnet 422, normal switch 412, resistance 110, 402—40 2—12, 401—2—12, helix of final test relay 196, earth.

C55. "Final pilot magnet." Battery, final pilot magnet 421, normal switch 411, 401—1—12, points of relay 196, earth.

45 Final pilot 401 in position 1—13 closes its test circuit C17 which had been open at 402—3—23 while 401 was restoring and at 401—6—0 while 402 was restoring. C17 is open also if the brushes are removed from 50 any contact bank.

Having thus described my invention, what I claim as new and desire to obtain by U. S. A. Letters Patent is:

1. In an automatic telephone system, a 55 ringing-starting relay, an automatic switch having busy-testing and speaking positions, and a ringing-starting circuit charging said relay and closed by said switch intermediate of said two positions.

60 2. In an automatic telephone system, a switch, a signal lamp, a relay, a circuit for said signal lamp through points of said relay when said switch is normal and a circuit through switch points in certain positions 65 of said switch other than normal.

3. In an automatic telephone system, a switch, a signal lamp, a relay, a circuit for said signal lamp through points of said relay and points of said switch when said switch is normal and a circuit through switch 70 points in certain positions of said switch other than normal.

4. In an automatic telephone system, a switch, a signal lamp, a relay, a circuit for said lamp through points of said relay when 75 said switch is normal, a circuit for said lamp through switch points when said switch is in certain positions other than normal, and means for operating said relay to close said first lamp circuit when said switch is normal but busy.

5. In an automatic telephone exchange, a set of switches all of which are required to be in operative condition to render any switch available for service, and a test circuit for selecting said set and running serially through all of the switches of the set.

6. In an automatic telephone exchange, a set of three switches all of which are required to be in operative condition to render any switch available for service, and a test circuit for selecting said set and running serially through all of the switches of the set.

7. In an automatic telephone exchange, a 95 set of switches all of which are required to render service, detachable brushes in said switches and a test circuit for selecting said set and running through detachable brushes in every switch.

8. In an automatic telephone exchange, a set of switches all of which are required to render service, detachable brushes in said switches, a test circuit for selecting said set and running through detachable brushes in 105 every switch and testing devices for selecting said set and operating to reject said set when any of said brushes are detached.

9. In an automatic telephone system, a plurality of levels of switching contacts, a 110 conductor joining a plurality of contacts, a brush constantly in contact with said contacts and in electrical connection with said conductor in all positions of said brush when said switch is assembled and a testing circuit through said brush.

10. In an automatic telephone system, a plurality of levels of switching contacts, a conductor joining a plurality of contacts, a brush constantly in contact with said contacts and in electrical connection with said conductor in all positions of said brush when said brush is assembled and a testing circuit through said brush and testing devices rendered unresponsive to said circuit 120 when said brush is separated from said contacts by disassembling said switch.

11. In a telephone system, a line, two searching switches both connecting ultimately with said line at the same time, two 130

- operating circuits for said two switches, two relays interrupting said two circuits independently, two test circuits controlling said two relays independently, by all of which said switches start simultaneously and stop independently in selective positions; and a further circuit for advancing one of said switches to said line.
12. In a telephone system, a line, two searching switches, two operating circuits for said two switches, two relays interrupting said two circuits independently, two test circuits controlling said two relays independently, by all of which said switches start simultaneously and stop independently in selective positions; a further operating circuit for starting one of said switches again; and a further test circuit for stopping said last mentioned switch upon said line, said line being then extended through both of said switches.
13. In a telephone system, a line, two searching switches, two operating circuits for said two switches, two relays interrupting said two circuits independently, two test circuits controlling said two relays independently, by all of which said switches move together and stop independently in selective positions; and a further circuit for advancing one of said switches whereby both of said switches are connected to said line; and a guard-wire test and a loop-line test operating jointly to determine the ultimate position of said last mentioned switch.
14. In a telephone system, a line, two searching switches operative to serve said line contemporaneously, means for advancing said two switches simultaneously into preliminary selective positions, and further means for advancing one of said switches to said line.
15. In a telephone system, a line, a line circuit for said line; speaking conductors for said line; a guard conductor for said line; two searching switches; means for moving said switches to preliminary selective positions, said means independent of said speaking and guard conductors; and further means, including one of said conductors, for positioning one of said switches in connection with said line, said line then extending through said two switches in series.
16. In a telephone system, a line, a line circuit for said line; speaking conductors for said line; a guard wire for said line; two searching switches both required to connect said line for conversation; means for moving said switches; means for stopping said switches in preliminary selective positions, said means independent of said speaking and guard conductors; and further means, including one of said conductors, for positioning one of said switches in connection with said line.
17. In a telephone system, a line, a line circuit for said line; speaking conductors for said line; a guard wire for said line; a linefinder switch; means for moving said switch to a preliminary selective position, 70 said means independent of said speaking and guard conductors; and further means, including one of said conductors, for moving said switch farther by the same mechanical propelling devices, thereby positioning said switch in connection with said line. 75
18. In a telephone system, a central office, a line, two switches for connecting with said line for contemporaneous service, circuits wholly within said central office for advancing said switches simultaneously and for stopping said switches in preliminary selective positions; a circuit for advancing one of said switches further; a circuit including said line; and a derived circuit for stopping said last mentioned switch on said line. 80
19. In a telephone system, a central office, a line, a switch, circuits wholly within said central office for advancing said switch and for stopping said switch in a preliminary selective position; a circuit for advancing said switch further by the same mechanical propelling devices; a circuit including said line; and a derived circuit for stopping said switch on said line. 85
20. In a telephone system, a central office, a line, a switch, circuits wholly within said central office for advancing said switch and for stopping said switch in a preliminary selective position; a circuit for advancing said switch further by the same mechanical propelling devices; a guard-test circuit and a line-loop-test circuit for stopping said switch on said line. 90
21. In a telephone system, a linefinder mechanism having two successive searches, the first search independent of the speaking or testing conductors individual to the line and the second dependent upon said conductors, the two searches being successive and being effected mechanically by the same mechanical propelling mechanism. 95
22. In a telephone system, a linefinder mechanism having two successive adjustments, the first adjustment independent of the speaking or testing conductors individual to the line, and the second adjustment dependent upon tests directly upon the speaking and guard conductors, the preliminary positions of adjustment being in some cases the final positions of adjustment. 100
23. In a telephone system, a line, a linefinder adjustable to engage said line, means common to a plurality of lines for adjusting said linefinder to a preliminary position, and circuits individual to the line for determining the ultimate adjustment of said linefinder, said preliminary adjustment being at times the ultimate adjustment. 115
24. In a telephone system, a line, other 120
- 125

- lines, a line finder common to all said lines and having movements of adjustment in but one direction; circuits each common to a plurality of lines for adjusting said linefinder preliminarily; and test circuits comprising in part conductors individual to said line for readjusting said line finder to engage said line.
25. In a telephone system, a line, other lines, a line finder common to all said lines and having movements of adjustment in but one direction; circuits each common to a plurality of lines for adjusting said linefinder preliminarily, and test circuits comprising in part conductors individual to said line for readjusting said linefinder to a further position of adjustment in engagement with said line.
26. In an electrical switch, a pair of brushes, a pair of contacts connected together, with which said brushes are in engagement when said brushes are at rest, one of said brushes adjusted to engage its contact late in the movement of the brushes toward their position of rest, the other of 25 said brushes adjusted to break engagement from its contact early in the movement of the brushes from their position of rest.
27. In an electrical switch, a pair of brushes, a pair of contacts connected together, with which said brushes are in engagement when said brushes are at rest, one of said brushes adjusted to engage its contact late in the movement of the brushes toward their position of rest, the other of 30 said brushes adjusted to break engagement from its contact early in the movement of the brushes from their position of rest and a circuit including both of said brushes.

Signed by me at Toronto, county of York, 40 and Province of Ontario, Canada.

DAVID S. HULFISH.
